Primary Examiner — Philip S Hyder(74) *Attorney, Agent, or Firm* — Erickson Kernell IP,
LLC; John C. McMahon(57) **CLAIM**

The ornamental design for a handle, as shown and described.

DESCRIPTION

FIG. 1 is a perspective view of a handle in accordance with the invention;

FIG. 2 is a first side elevational view of the handle with the second side elevational view of the handle being a mirror image thereof;

FIG. 3 is a rear elevational view of the handle with the front elevational view of the handle being a mirror image thereof;

FIG. 4 is a bottom plan view of the handle; and,

FIG. 5 is a top plan view of the handle.
